UNITED STATES PATENT OFFICE

WALDEMAR L. LINDGREN, OF WAUKEGAN, ILLINOIS, ASSIGNOR OF ONE-HALF TO JOHN E. ERICSSON, OF CHICAGO, ILLINOIS

DISHWASHING APPARATUS

Application filed January 19, 1931. Serial No. 509,658.

My invention is concerned with dish washing apparatus, and is designed to produce a simple structure, adapted to be placed in a household sink, and which washes the dishes 5 carried therethrough by the use of the hot water supplied by the sink without the necessity of employing any pumping mechanism.

It is further concerned with such a structure in which the conveying mechanism, constituting the major portion of the apparatus, is removably mounted in the sink, which is supplied with spraying mechanism permanently mounted therein in such a manner that it can be swung out of the way, leaving 15 the sink free for ordinary use when the conveying mechanism is removed.

It is further concerned with a novel conveying mechanism that is adapted to carry and deliver table cutlery, as well as dishes, 20 so that table cutlery can be efficiently and quickly washed.

To these ends, it consists of certain novel combinations of elements, as will be herein-after fully described, and particularly pointed out in the claims.

To illustrate my invention, I annex hereto three sheets of drawings, in which the same reference characters are used to designate identical parts in all the figures, of which,—

Fig. 1 is a front elevation of the apparatus in partial section, on the line 1—1 of Fig. 3;

Fig. 2 is a plan view in section on the line 2—2 of Fig. 1;

Fig. 3 is a vertical section on the line 3—3 of Fig. 1;

Fig. 4 (Sheet 3) is a detail in section showing a part of the conveyor belt;

Fig. 5 is a perspective view of one of the links making up said belt;

Fig. 6 (Sheet 1) is a detail of a portion of the mechanism shown in Fig. 2, but with the conveyor belt and parts above it removed.

In its preferred form, it consists of certain novel spraying mechanism made a part of the sink fixtures, together with an electric motor mounted thereon, and gearing from the motor detachably connected to the conveying mechanism which it drives, and which is removably mounted in the sink, and designed so 45 that it is kept washed clean by the same water

that washes the dishes, which water is always fresh, and is never used over.

Beginning with the spraying mechanism, the hot and cold water pipes 21 are passed through the rear wall 23 of the sink, as best 55 shown in Fig. 16, and are suitably connected to the mixer forming a part of the casting 36, and seen in dotted lines in Fig. 1 and in cross section in Fig. 3, and having the cocks 47 for controlling the temperature.

The casting 36, which is employed as a substitute for piping connections, is rectangular in its general shape, and has secured on the opposite sides, near the lower end thereof, the rubber plugs 40 secured in the rear face 60

thereof and resting against the rear wall 23 of the sink, the casting being supported from said rear wall through the medium of the two conduits 29 by the connections already described. The body of the casting has projecting rearwardly from the vertical walls thereof the flanges 41, which are interrupted by the recess 42 to permit the passage of the conduits 29, connected to the hot and cold 65

water supply pipes 21. It has at its upper 70 end the rearwardly projecting flange 43, which has bolted thereon the bracket 44 which furnishes the support for the small electric motor 45 secured thereto, and which furnishes the driving power for the conveying mechanism, as will be hereinafter fully described.

I form in the front part of the casting a lug 75 56 which has a vertically tapered interior forming a valve seat, in which is mounted the tapered end of the faucet 59 adapted to

turn in the bearing formed by the valve seat, and secured in place by the nut 60. The valve 80 seat for the faucet 59 is connected with the mixer so that when the faucet is turned parallel to the face of the sink, no water can pass therethrough, but when it is turned at right angles, the water will pass out of the faucet 85

for ordinary use. Formed in the casting 36 are suitable passages from the conduits 29 to the mixer, and from the mixer other passages 90 extend forwardly into the pair of lugs 64 located substantially at the lower corners of the casting, and having the tapered valve seats 95 65 therein to receive the corresponding tapered ends 66 of the lower soapy-water 100

spraying member 67 and the lower rinse water spray member 68, the ends 66 being constructed as shown in Fig. 3, and having the inlet ends shaped to co-operate with the passage 63 when said members 67 and 68 extend at right angles to the face of the sink, in which position they are operative as spray members, and to have the water shut off when they are turned parallel to the rear wall of the sink. 5 From the rear ends of the passages 63, the vertical passages 69 extend upward through the casting to the pair of lugs 70 projecting forwardly from the upper corners of the casting and having therein the tapered valve seats 71, in which are swiveled the tapered ends 72 of the top soapy-water spray member 73 and the rinse-water spray member 74, the swiveled ends of which are constructed the same as the ends of the faucet 59 and the lower 10 spray members 67 and 68.

The upper soap water spray member 73 is shown in detail and described in my Patent No. 1,798,428, dated March 31, 1931, and it will be understood that the lower soapy-water spray member 67 is identical therewith except that its position is inverted to throw the water upward through the skeleton conveyor to be hereinafter described, while the upper spray member throws the water downward. It will also be noted that with the arrangement of the conduits shown, the greater pressure is applied to the lower spray members, as they have to overcome the resistance of gravity in throwing the water upward, whereas the upper spray members have the benefit of it. The connecting pipe of the spray member 73 opens at its outer end downwardly into the body portion 75, which is a rectangular casing with its outer end open, and closed in use by the end 76 of the soap holder. The spraying outlets 86 are formed in the tubular extension 87 formed on the bottom of the body portion, and having at the bottom thereof the flanges 88 cooperating with the conveyor cover, as will be hereinafter described.

As seen in Figs. 1 and 3, the rinse-water spraying members 68 and 74 are tubular in their cross section and furnished with the same perforations 86, the upper spray member being likewise furnished with the flanges 88 of the tubular extension 87 of the upper soapy-water spray member. These flanges are not needed and do not exist in the lower spray members 67 and 68. While a single row of the perforations 86 are sufficient for the spray members 68, 73 and 74, I find that better results are secured with the spray member 67 by having three rows of perforations, 60 as the soapy water has to pass upward through the skeleton conveyor now to be described.

The armature shaft of the motor 45 is connected through a worm and a worm gear wheel in the gear casing 92 with the upper

end of the shaft 91, the lower end of which is journaled in bearings formed in the gear casing 93, and has thereon a worm meshing with the worm gear wheel pinned on the short shaft 96 journaled in suitable bearings in the gear casing 93. Pinned on the forward end of the shaft 96 is the clutch member 100, which has a lug 101 cooperating with a lug 102 on the clutch member 103 which is held frictionally by means which need not be described on a sleeve which is pinned on to the horizontal drive shaft 105 of the conveyor. The object of this slip connection is so that, in case the conveyor should become jammed at any time, the slip clutch will release and allow the conveyor to stop in spite of the continued motion of the motor. 70 75 80

Referring now more especially to sheets 1, 2 and 3, the conveyor will be seen to consist of a framework made up of the two side-piece castings 110 and 111, of substantially the same design, except that they face in opposite directions, the outer casting 110 having secured thereon a pair of lugs or brackets 112 adapted to rest on the forward edge of the sink, while the rear side piece 111 has projecting from the top thereof a pair of lugs 113 having apertures therein adapted to receive the upturned ends of the lugs 114 projecting from the front face of the casting 36 for the purpose of supporting that side of the carrier frame. Inasmuch as these are the only connections of the carrier or conveying mechanism with the sink and casting 36, it will be obvious that the conveying mechanism can be lifted out of the sink, the clutch members 100 and 103 permitting the separation of the driving connections when the conveying mechanism is to be removed. With the spraying mechanisms 67, 68, 73 and 74 swung to their inoperative positions parallel to the rear wall of the sink, it will be obvious that the sink can then be used in the ordinary manner. The receiving or left-hand ends of the side pieces are connected by the plate 115, best shown in Fig. 2, secured thereto by the screws 116, and this plate is preferably provided on its upper surface with the parallel longitudinally-extending ribs 117, and between these ribs I preferably form the numerous perforations 118, and at the center is located the curved recess 119, all of which serves to assist in convenient handling of the dishes on this receiving plate 115, from which they are shoved on to the conveyor proper. The side pieces are also connected at this end by the cross bar 120 located in the plane of the axes of the wheels. At the delivery end, the side frames are connected by the receiving plate 121, similar to the plate 115, it being provided with the ribs 117 and the perforations 118, but it preferably has three recesses 122 corresponding in function to the recess 119, and being employed so that the dishes can be 90 95 100 105 110 115 120 125 130

more readily removed therefrom as they are discharged on this plate by the conveying mechanism. The side pieces are also connected at this end by the cross bar 123, which 5 will be described more in detail farther on.

The shaft 105 is journaled in bearings formed in the side plates 110 and 111, and has secured thereon at its outer end, a short distance inside of the side pieces 110, the 10 sprocket wheel 124, seen in Figs. 2 and 3, the teeth of which mesh with rods 125 forming the transverse members of the skeleton conveying belt, the longitudinal members of which are formed by the links 126, one of 15 which is shown detached in Fig. 5, which co-operate with the annular grooves 127 formed in the rods 125 at the ends thereof and at equi-spaced distances throughout their 20 length so as to form an endless skeleton conveyor with rectangular apertures therein, as best seen in Fig. 2. The links 126 have apertures 128 in the ends thereof, which apertures are of the shape shown in Fig. 5, the 25 smaller ends being of the external diameter of the grooves 127, while the large inner ends are of slightly greater diameter than that of the rods 125, so that the rods and links can be assembled. Preferably journaled in suitable 30 bearings at the ends of the side pieces are the rods or shafts 129 and 130, which have secured or journaled on the ends thereof adjacent the inner faces of the side pieces 110 and 111 the four sprocket wheels 131 which co-operate with the rods 125 of the endless 35 conveyor. With the structure thus far described, it will be obvious that dishes shoved from the table 115 on to the endless conveyor will be carried through the apparatus and delivered therefrom at the other end, having 40 been first sprayed from both above and below with the soapy water, and then similarly rinsed with clear hot water.

In order to handle table cutlery, I have found that it is necessary to make special provisions to prevent the cutlery from getting into the conveyor, and to prevent this I employ the following mechanism. On the shaft 129 immediately adjacent the left-hand pair of wheels 131, I employ a pair of brackets 132, on the upper end of which is secured the forward curved end of the flat sheet-metal plate 133, immediately adjacent which the conveyor belt travels. The forward end of the plate is supported by the lugs 134 projecting inwardly from the side frames and having extensions of the plate 133 secured thereto. This plate prevents the cutlery from getting into the conveyor as it starts. At the other end, I employ another sheet-metal plate 135, the inner end of which is secured to the lugs 136 projecting inwardly from the side frames, and the outer end is similarly secured to the brackets 137, similar to the brackets 132 and positioned on the shaft or rod 130 adjacent the wheels 131. The inner

end of this plate is some distance below the conveyor belt, and slopes upward, as seen in Fig. 1, until it is in contact therewith, and is for the rest of its length curved on the necessary arc of a circle with the shaft 130 as a center. If any of the cutlery has gotten through the belt, when it reaches the plate 135 it is contacted thereby, and is cammed up and out of the belt during its passage over the plate. Still further to insure the discharge 70 of cutlery from the conveyor belt at the discharge point, I secure on the under side of the plate 135, at each end thereof, a leaf spring 138, and to the free ends of this leaf spring I secure the rod 139, which has journaled thereon at intervals the disks 140 which project through slots 141 placed in the plate 135 to receive them. To prevent the possibility of these disks being misplaced by being pressed back entirely through the slots 141 and then slid sidewise, I limit the inward movement of the shaft 78 by passing it through a pair of slotted brackets 145 secured to the ends of the plate 135. From an inspection of Fig. 1, it will be obvious that as the 75 rods 125 pass the disks 140, they will force them back toward the shaft 130, and as each rod passes, the disks will be thrown back to the position shown in Fig. 1 by the springs 138, thus knocking any cutlery they may contact with off from the conveyor. In order to get the plate 135 at its highest point substantially in contact with the rods 125, I form in the plate the elongated slots 164, best shown in Fig. 6, in which the links travel as they 80 curve around the end.

The cross piece 123 has at its upper end an upwardly and rearwardly projecting portion 146, which has formed therein the recesses 147, shown in Fig. 6, through which the outer portions of the links 126 pass in order to make sure that any cutlery will be taken off from the conveyor by the action of this extension 146. I preferably provide the lower portion 105 of the cross piece 123 with a plate 148 hinged thereto and adapted to be normally directed downward, as shown in Fig. 1, so that the cutlery will be directed thereby over the end of the sink, instead of dropping down beneath the end of the conveyor, where it could not be readily gotten at. As it is sometimes desirable to get to the bottom of the sink underneath the end of the conveyor, I provide the under side of the plate 121 with one or more spring catches 149 adapted to catch and hold the plate in its elevated dotted-line position of Fig. 1. It will also be obvious that by hinging the plate 148, it will accommodate itself to variations in the height of the end of the sink upon which it rests, as 110 seen in Fig. 1.

When the machine is used to wash dishes, it is necessary to bridge the gap between the discharge portion of the conveyor and the adjacent edge of the table 121, and, for this 115 120 125 130

purpose, I provide the bridge plate 150, which consists of a sheet-metal plate long enough so that its ends rest on the flanges 151 projecting inwardly from the side pieces 110 and 111, and the outer side of this plate is rigidly secured on the bail 152, which has its ends 153 pivoted in suitable apertures formed in the adjacent portions of the side frames. The bail is shaped as shown in Fig. 2, so that portions thereof will extend beyond the sides of the conveyor so that the switch plate can be conveniently manipulated. In washing dishes, the plate is in the full-line position shown in Fig. 1; but when it is used for washing cutlery, it is swung back to the dotted-line position, leaving space for the cutlery to pass downward and beneath the plate 121.

The apparatus as thus far described can be employed for washing dishes and table cutlery, but water would be splashed from off the dishes and conveyor, and to prevent this, I employ the cover shown in Figs. 1, 2 and 3, where it will be seen that I employ a metallic cover 154 which has a vertical back piece 155 and a vertical front piece 156, with their lower edges resting on the offsets 157 formed on the top of the side pieces 110 and 111 for this purpose. The top is flat, except for the inverted trough-like portions 158, which have slots 159 in their tops to receive the discharge tube portions of the spray members 73 and 74, and the flanges 88 previously mentioned as employed with said spray members prevent the water being splashed upwardly through these slots. There is enough clearance so that the cover 154 can be lifted enough to unseat the front portion 156 from the offset 157, after which the cover can be withdrawn horizontally off of the machine, after which the conveying mechanism is then free to be lifted out of the sink, the apertures 160 being placed in the side plate 111 to permit the conveying mechanism to be moved into and out of place over the spraying members 67 and 68. To prevent the water splashing out of the ends of the cover, and still not interfere with the passage of the dishes into and out of it, I provide at each end a flexible curtain consisting of two rows of chains 161 made of flat links formed from sheet-metal, one row being secured on each side of the ribs 162 projecting downwardly from the top of the cover near each end. As seen in Fig. 3, the chains of each row have the links spaced apart a little distance, and the spaces thus formed are overlapped by the chains of the adjacent row, which are staggered therewith for this purpose. With the construction described, it will be obvious that water cannot pass the curtains, while they do not offer serious resistance to the passage of the dishes.

As the water pressure at the sink may vary very materially in different buildings or on

different floors of the same building, it is essential to provide means for controlling the pressure, to suit each installation. To this end I make the internal diameter of the tubes 68, 73, 74 and 76 great enough to take care of the lowest pressure in the sink that has to be provided for, and for greater pressures I provide constrictions 163 in the tubes by reducing the diameter of the core upon which each is cast at the point where the constriction is to occur, and it will be understood that the size of the constriction will vary with the specific pressure at which it is to be used, the greater the pressure, the greater the constriction.

The operation of the apparatus will be readily apparent.

While I have herein partially disclosed a novel casting forming a substitute for the piping shown in my Patent No. 1,798,426, I do not herein claim the same, as it is fully illustrated and claimed in my application No. 502,315, filed December 15, 1930.

While I have shown and described my invention as embodied in the form which I at present consider best adapted to carry out its purposes, it will be understood that it is capable of modifications, and I do not desire to be limited in the interpretation of the following claims except as may be necessitated by the state of the prior art.

What I do claim as my invention, and desire to secure by Letters Patent of the United States, is:

1. In a dish-washing machine, the combination with a frame, of a horizontally movable skeleton carrier mounted therein adapted to carry table cutlery thereon, means for moving said carrier, a member over which the cutlery may be discharged below the end of the conveyor pivoted to the frame, a discharge table carried by said frame above said member, and a spring catch secured to the discharge table to hold said member in its raised position.

2. In a dish-washing machine, the combination with a frame, of a horizontally movable skeleton carrier mounted therein adapted to carry table cutlery thereon, means for moving said carrier, a member over which the cutlery may be discharged below the end of the conveyor pivoted to the frame, a discharge table carried by said frame above said member, a switch plate pivoted on the frame adjacent the table to direct the cutlery on to the table or to allow it to pass over the member, depending upon how it is adjusted, and a spring catch secured to the discharge table to hold said member in its raised position.

In witness whereof, I have hereunto set my hand this 15th day of January, 1931.

WALDEMAR L. LINDGREN.
